[57] CLAIM

The ornamental design for a combined pharmaceutical container and cap, as shown and described.

DESCRIPTION

FIG. 1 is a perspective view of a combined pharmaceutical container and cap embodying our new design;
FIG. 2 is a first side elevational view thereof;
FIG. 3 is a second side elevational view thereof, the second side being opposite the first side;
FIG. 4 is a top view thereof; and,
FIG. 5 is a bottom view thereof.

The broken line showing is for illustrative purposes only and forms no part of the claimed design.
